UNITED STATES PATENT OFFICE.

FREDERIC E. BAGER, OF KENOSHA, WISCONSIN, ASSIGNOR TO FREDERICK C. AUSTIN,
OF CHICAGO, ILLINOIS.

BANK-SUPPORT FOR DITCHES.

1,234,716.

Specification of Letters Patent.

Patented July 31, 1917.

Application filed December 31, 1915. Serial No. 69,549.

To all whom it may concern:

Be it known that I, FREDERIC E. BAGER, a citizen of the United States of America, and resident of Kenosha, Kenosha county, 5 Wisconsin, have invented a certain new and useful Improvement in Bank-Supports for Ditches, of which the following is a specification.

My invention relates to apparatus for use 10 in making trenches or ditches, and more particularly to machinery or devices for this purpose having means for holding or supporting the sides of the trench or ditch, thereby to prevent the banks from caving in 15 during the construction of the trench, whereby, for example, tile can be laid in the bottom of the trench without danger of the dirt falling at the sides thereof.

Generally stated, the object of my invention 20 is to provide an improved and comparatively simple bank support which will hang in the ditch or trench and bear against the sides thereof, thereby to prevent the banks from caving in, and which can be moved 25 readily along the banks as fast as the work of excavation progresses.

The special object is to provide a bank support of this character in which simple and satisfactory provisions are made for adjustment of the structure to suit the requirements of trenches or ditches of different widths and heights.

It is also an object to provide an improved bank support which can be hitched to the 35 trench machine and which will follow the latter along the trench or ditch, the entire weight of the support, however, being sustained by its own wheels or similar means, and no additional weight being imposed 40 on the trenching machine, the latter simply providing the motive power for drawing the said bank support ahead.

It is also an object to provide certain details and features of construction and combinations tending to increase the general efficiency and desirability of a bank support or dirt shield of this particular character.

To the foregoing and other useful ends, my invention consists in matters hereinafter 50 set forth and claimed.

In the accompanying drawings, Figure 1

is a side elevation of the rear portion of a trench machine, showing the same in operation, and including a side elevation of a bank support embodying the principles of 55 my invention.

Fig. 2 is a plan of the said bank support.

Fig. 3 is a transverse vertical section of the said bank support, illustrating the method of use thereof for preventing the 60 banks from caving in at the sides of the trench.

Fig. 4 is an enlarged detail section on line 4-4 in Fig. 3.

As thus illustrated, my invention comprises a pair of dirt shields or flat members A which are of a size and shape to extend downward into the ditch and bear against the sides thereof. (See Fig. 3.) The front and rear axles B and C are provided at their 70 ends with wheels b and c, these two axles being connected by parallel bars D which are disposed between the said wheels and the members A, whereby the said axles and bars combine to form a rectangular frame 75 having wheels at the four corners thereof. Vertical angle irons E are secured to the inner surfaces of the members A, these angle irons being arranged in pairs, and the members of each pair being disposed at opposite sides of one of the axles. These angle irons are provided with openings e disposed at different heights thereon, and bolts 80 F are inserted through these openings and above the said axles, thus providing means 85 for supporting the members A upon the axles. With this arrangement, and by removing the bolts F and inserting them in different holes e, in a manner that will be readily understood, the members A can be 90 supported at different heights and in accordance with the requirements of the work. In order to permit this adjustment, the members A are provided with vertical slots a, each slot being disposed between the members 95 of one of the pairs of angle irons E, and the latter extending a suitable distance above the upper edges of said members. Collars G are secured to the axles B and C to bear against the angle irons E, thereby to properly 100 space the members A a suitable distance apart, and similar adjustable collars H bear

against the outer sides of said members. By adjusting these collars along the axles B and C, the distance between the members A can be changed to suit the requirements—
5 that is to say, the structure as a whole can be adapted for use in connection with trenches of different widths.

In use, the members A are maintained the desired distance apart by adjustable spreaders I which may be in the form of screws having heads which bear against the strips or beams i on the inner surfaces of the two members. As shown, each spreader comprises a pair of screws 1 and 1 adjustably
10 connected by a threaded sleeve 2, and by rotating this sleeve the length of the spreader can be changed or varied at will. By means of these spreaders the two members A are held firmly against the sides of the ditch.

20 At its forward end, the bank support is provided with a pair of plates J. The plates J are pivoted at their lower ends to the lower portions of the members A, thereby providing a horizontal axis j about which these
25 plates can be swung back and forth in the vertical planes thereof, each plate being immediately inside of one of said members. By means of holes 3 and bolts 4, these plates J can be held in different positions, each
30 plate projecting some distance above the top of the ditch.

When employed in conjunction with a trench machine, ropes or other connections K connect the rear end of the trench machine body with the plates k on the forward ends of the bars D, thereby providing a draft connection at each side of the ditch. These connections are preferably of a length to bring the plates J close to the trench cutting apparatus L, the latter comprising the usual and well known endless link belt l provided with buckets 5 which carry the dirt upward and discharge the same at the upper end of the digging beam 6 which
45 forms a frame for the excavating apparatus. The plates J can be adjusted until they embrace the path of travel of the downwardly traveling buckets.

50 Thus, while the machine is traveling forward, the sides of the ditch or trench are held firmly against caving in behind the excavating apparatus. Workmen can be laying tile in the bottom of the ditch at this point without danger of the dirt falling at opposite sides thereof. The bank support thus constructed moves slowly forward with the trench machine, and that portion of the trench immediately in the rear of the excavating apparatus is always safe against
55 caving in, so that tile can be laid or other kinds of work done at this point without danger of interference by falling dirt.

What I claim as my invention is:

65 1. A trench machine having an apparatus for cutting a trench, and a structure travel-

ing above ground on the banks of the trench behind said apparatus and having means depending therefrom to support the sides of the trench close to said apparatus, thereby to prevent caving-in of the banks.

70

2. A trench machine having an apparatus for cutting a trench, and a structure traveling above ground on the banks of the trench behind said apparatus and arranged to support the sides of the trench, thereby to prevent caving-in of the banks, said means extending forward over the rear end of said apparatus and including a member which has a surface to bear against the side of the trench, to slide thereon during forward movement of the machine, and devices to hold said member against the bank.

75

3. A trench machine having an apparatus for cutting a trench, and a structure traveling above ground on the banks of the trench behind said apparatus and having means depending therefrom to support the sides of the trench, thereby to prevent caving-in of the banks, said means extending forward over the rear end of said apparatus and including oppositely disposed members which have outer surfaces to bear against the sides of the trench, to slide thereon during forward movement of the machine, and adjustable devices between said members to hold them apart and against the banks.

80

4. A trench machine having an apparatus for cutting a trench, and means traveling behind said apparatus to support the sides of the trench, thereby to prevent caving-in of the banks, said means including a truck having wheels which travel on the banks of the trench, oppositely disposed members hung on said truck to extend into the trench, and adjustable devices between said members to hold them against the banks.

85

5. A trench machine having an apparatus for cutting a trench, and a structure traveling above ground on the banks of the trench behind said apparatus and having means depending therefrom to support the sides of the trench, thereby to prevent caving-in of the banks, said means including oppositely disposed members which have outer surfaces to bear against the sides of the trench, to slide thereon during forward movement of the machine, and adjustable devices between said members to hold them apart and against the banks, said members being adjustable up and down and toward and away from each other.

90

6. A trench machine having an apparatus for cutting a trench, and means traveling behind said apparatus to support the sides of the trench, thereby to prevent caving-in of the banks, said means including a truck having wheels which travel on the banks of the trench, oppositely disposed members hung on said truck to extend into the trench, and adjustable devices between said mem-

bers to hold them against the banks, said members being adjustable up and down and toward and away from each other.

7. A trench machine having an apparatus 5 for cutting a trench, and means traveling behind said apparatus to support the sides of the trench, thereby to prevent caving-in of the banks, said means including oppositely disposed members which have outer 10 surfaces to bear against the sides of the trench, to slide thereon during forward movement of the machine, adjustable devices between said members to hold them apart and against the banks, and adjustable 15 guards pivoted at their lower ends to the lower front portions of said members in position to swing forward and embrace the rear of said apparatus.

8. A trench machine having an apparatus 20 for cutting a trench, and means traveling behind said apparatus to support the sides of the trench, thereby to prevent caving-in of the banks, said means including a truck

having wheels which travel on the banks of the trench, oppositely disposed members 25 hung on said truck to extend into the trench, adjustable devices between said members to hold them against the banks, and adjustable guards pivoted at their lower ends to the lower front portions of said 30 members in position to swing forward and embrace the rear of said apparatus.

9. A bank support for ditches, comprising a truck provided with transverse axles having wheels which travel on the banks 35 of the trench, oppositely disposed members hung on said axles to extend into the trench, and adjustable devices between said members to hold them against the banks.

10. The said machine, as set forth in 40 claim 9, said members being adjustable up and down and toward and away from each other on said axles.

Signed by me at Chicago, Illinois, this 11th day of December, 1915.

FREDERIC E. BAGER.
